JOHN JOSEPH DALLIER, OF GREAT LAKES, ILLINOIS, ASSIGNOR OF TEN ONE-HUNDREDTHS TO FRED V. CLARK, OF GREAT LAKES, ILLINOIS.

TORPEDO-STEERING MECHANISM.

1,098,230.

Specification of Letters Patent.

Patented May 26, 1914.

Application filed May 28, 1913. Serial No. 770,358.

To all whom it may concern:

Be it known that I, JOHN J. DALLIER, a citizen of the United States, and a resident of Great Lakes, North Chicago, in the county of Lake and State of Illinois, formerly of the city of New York, borough of Queens, in the county of Queens and State of New York, have invented a new and Improved Torpedo-Steering Mechanism, of which the following is a full, clear, and exact description.

Among the principal objects which the present invention has in view are: to provide means for maintaining a torpedo on a relatively straight course; to provide an operating mechanism for a steering gear to effect the above-mentioned purposes easily and positively, and to provide operating means for the steering rudder, said means being removable from service position without loss of time and without undue effort.

One embodiment of the present invention is shown in the accompanying drawings, in which—

25 Figure 1 is a sectional elevation of the rear end fragment of a torpedo, operating parts therefor, and a steering gear connected therewith constructed and arranged in accordance with the present invention; Fig. 2 is a top plan view of an automatic mechanism for controlling the torpedo steering mechanism; Fig. 3 is a sectional elevation of the same; Fig. 4 is a detail view showing the automatic mechanism for controlling the steering mechanism in operative position.

As seen in the drawings, the torpedo body 9 is provided with an opening to receive the body section 10, from which a fin section 11 is extended in line with a tail fin 12 of the 40 torpedo.

The body section 10 is enlarged substantially as shown in Fig. 1 of the drawings, to form a level table 13, on which is mounted standards 14 to support guide rails 15. The 45 guide rails 15 are best seen in Fig. 2 of the drawings. Said rails are grooved along the edges of each to support a carrier 16. The carrier 16 is rapidly reciprocated longitudinally between the rails 15, which movement 50 is utilized to operate as a constant corrective or control for the main vertical steering rudders 17.

The rudders 17 have a plurality of blades, each connected by means of a short post 18

with a yoke 19 disposed within the tail casting 20 of the torpedo, and there connected with a piston rod 21. The piston rod 21 is provided with a piston 22, which is reciprocatively mounted in a cylinder 23, to which compressed air, gas or steam is admitted by means of port passages 24.

The passages 24 are opened or closed by a valve 25, which valve is provided with a valve rod 26, the opposite end of which is pivotally connected to a bell crank lever 27. 65 The bell crank lever 27 is pivotally mounted by means of a pin 28 on one of the rails 15.

The bell crank lever 27 is rocked on its pivot by the carrier 16 when a blade 29 is moved in the path of either of the arms 30 or 31. The arm 31 is rigidly connected with the bell crank lever 27. The arm 30 is a portion of a bell crank lever 32 which is pivotally mounted on the rail 15 opposite that supporting the bell crank lever 27. 75 The bell crank lever 32 is connected to the bell crank lever 27 by means of a link rod 33, all as shown in Fig. 2 of the drawings.

From the construction it will be seen that as the blade 29 is brought in contact with 80 one or the other of the arms 30 or 31, the valve rod 26 and valve 25 connected therewith are moved to the left or right respectively, to expose the port at the right of the cylinder 23 to receive pressure from a chest 34, while the port at the left of said cylinder is opened to exhaust through a port 35.

The engagement by the blade 29 of the arms 30 and 31 is dependent on the swing of a course-correcting plane 36 which is supported in bearings in the fin section 11 to lie normally flush therewith, which position it will assume when the water pressure on said plane is equal at opposite sides thereof. Whenever, in the operation of the torpedo, the water pressure on one side becomes greater than on the other, the plane 36, yielding thereto, turns upon its pivot, together with the post 37 and the head 38 mounted thereon. The head 38 is extended 95 toward the path of the carrier 16. The end of the head is shaped to pass between the fingers 39 and 40 of a rocking plate 41 when said plate is in position so that the blade 29 passes between the ends of the arms 30 and 31. 100 105

When for any reason the plane 36 is deflected relative to the axis of the torpedo generally caused by the torpedo swinging

from its initial course—the head 38 is rotated to engage one of the fingers 39 or 40, which rocks the plate 41 in such manner as to cause the blade 29 to engage one of the 5 arms 30 or 31, and to thereby rock the lever 27 to move the valve 25 in the manner above set forth.

The arrangement of the plane 36, the rudders 17 and mechanism operatively connecting the same is such that the rudders 17 are moved by the operation of the piston 22 and rod 21 in the direction opposite to that to which the plane 36 is deflected. In other words, if the torpedo turns from its course 15 to the left, the pressure on the right-hand side holds the plane 36 in its initial position, or moves the same in relation to the body of the torpedo to the left thereof. This movement of the plane 36 to the left operates 20 the valve mechanism of the cylinder 23, to move the piston 22 therein to deflect the rudders 17 to the right of the body of the torpedo, operating as a corrective to bring the nose of the torpedo up into the initial course. 25 As the torpedo rights its position, the plane 36 swings relatively to a plane flush with the fin section 11, or parallel to the longitudinal axis of the torpedo. If, in swinging in answer to the impulse given by the rudder 17, the 30 torpedo now pays off to the right, the pressure of the water on the left side of the plane 36 holding the same in the manner above described, rotates the same relatively to the right of the new position of the torpedo, when the head 38 swings into the path of the opposite finger 39 or 40 to rotate the plate 41 so that the blade 29 interferes with the opposite arm 30 or 31, as the case may be, and reverses the rock of the lever 27 and 40 the operative position of the valve 25 connected therewith, to the end that the piston 22 is moved to throw the rudders 17 to the left of the axis of the torpedo, swinging the nose again to the initial course.

The operation above described is dependent on the reciprocation of the carrier 16. To this end the carrier 16 is furnished with a standing pin 42 which extends into a cam slot 43 formed in a collar 44 which is mounted on the driving shaft 45 of the torpedo. The slot 43 is inclined to the vertical sufficiently to move the pin 42 and carrier 16 and plate 41 connected therewith so that the fingers 39 and 40 thereof pass the advanced edge of the head 38.

The expenditure of force necessary to move the carrier 16 either outward or inward is relatively slight, the pitch of the slot 43 being relatively small.

Claims—

1. In a torpedo having a propeller driving shaft; a steering mechanism comprising a steering rudder; power mechanism to operate said rudder; a throttle mechanism, for said power mechanism, embodying two oppositely-acting members; a transmission mechanism operatively connecting said propeller driving shaft and said throttle mechanism; and a course-correcting plane pivotally mounted and normally held by the pressure of water on the sides thereof parallel with the initial course of the torpedo, said plane having a rocking member movable to engage successively said oppositely-acting members. 60

2. In a mechanism such as described; a constant rotary driving member; a steering rudder; an independent power mechanism for operating said steering rudder; a translating mechanism operatively connecting said rotary member and power mechanism, said translating mechanism embodying a carrier reciprocatively connected with said driving member; a rocking member mounted on said carrier; a plurality of rocking levers disposed in the path of said rocking member to be moved by said member successively; a correcting plane pivotally mounted in contact with the water in which the torpedo floats; and means connected 80 with said plane for shifting said rocking member as said plane is moved laterally with reference to the longitudinal axis of the torpedo. 85

3. In a mechanism as characterized; a steering rudder; a piston operatively connected therewith; an operating cylinder for said piston, said cylinder having ports at opposite ends; a sliding valve controlling said ports; a valve rod; a rocking lever operatively connected with said rod; oppositely-extended swinging arms operatively connected with said rocking lever to operate the same in relatively reverse directions; a reciprocating member movable to engage or avoid said arms; and a course-correcting plane operable by water pressure, having means for moving said reciprocating member to successively engage each of said swinging arms. 100

In testimony whereof I have signed my name to this specification in the presence of two subscribing witnesses.

JOHN JOSEPH DALLIER.
